CARTON

Perry Belden, Lansdale, Pa., assignor to National Union Radio Corporation, Newark, N. J., a corporation of Delaware

Application May 18, 1944, Serial No. 536,091

2 Claims. (Cl. 229—6)

The present invention relates to a carton designed primarily for the packaging of miniature radio tubes.

At the present time, conservation of paper is a vital necessity in the war effort, and any form of packaging which tends to save paper is encouraged by the government. Furthermore, any improved, simplified form of radio tube carton is always welcomed by the industry because it effects economies in assembly which cheapens the packaging costs.

It is therefore an object of the present invention to provide a one-piece carton so designed as to reduce very substantially the amount of paper-board required for the making thereof.

Another object is to simplify the construction of a carton so that the complete carton may be stamped from a single blank piece of packing material die-cut and suitably scored for folding purposes.

Another object of the invention is the provision of a one-piece carton which when assembled does not require stitching or gluing to hold the carton in an assembled position.

Another object is the provision of a cut-out blank provided to form side walls when folded and also having laterally extending portions adapted to fold in such a manner that transverse supporting platforms are formed between which the tube may be suspended.

Another object of the invention is to provide a carton made from a single blank consisting of two major portions, one designed to fold into a filler member in which the tube is supported, and the other adapted to provide an outer wrapper portion which folds and locks about the filler member.

A further object of the invention is the provision of a cardboard blank having a general body portion and a laterally formed portion contiguous with one end of the body portion capable of folding into a tube-supporting filler element, and the body portion then wrapped around the filler.

Other objects will manifest themselves as the description proceeds.

Referring to the accompanying drawing:

Fig. 1 is an extended view or development of a one-piece blank forming the filler member and also constituting side walls of a carton embodying my invention;

Fig. 2 is a view, partly in development and partly in perspective, illustrating the filler member in a partly folded condition;

Fig. 3 is a view similar to Fig. 2, except the filler member is shown completely folded;

Fig. 4 is a perspective view showing the filler member completely folded and partially wrapped within the outer container portion of the carton; and

Fig. 5 is a perspective view, partly broken away, illustrating the tube packaged and sealed within the completely folded carton.

Referring to the accompanying drawings, particularly Fig. 1, it will be seen that the carton is comprised of a one-piece blank designated generally by the reference character 1, which blank consists of a major longitudinal wrapper portion 2 and a major filler portion 3 extending laterally therefrom. The portion 2 is provided with transverse score lines 4 dividing it into a series of sections 5 to 9 adapted to constitute side walls when folded along the score lines 4, thus forming an outside wrapper for the filler element. The lateral body portion 3 is adapted to form a filler element for the outer wrapper portion and may comprise a wall section 10 which is continuous with but somewhat less in length than the side wall sections 5 to 9. Adjoining the wall section 10 is a top section 11 and a bottom section 12. The sections 11 and 12 are provided with die-cut apertures 13 and 14 respectively, these apertures being circular in shape and in axial alignment with respect to the wall portion 10. It will be noted that the aperture 13 is smaller than the aperture 14, the reason being that the tip portion 15 of the tube is intended to project through the aperture 13 while the prongs 17 of the base project through the aperture 14, without permitting the base to protrude through said aperture 14 (see Figs. 3 to 5). It will thus be seen that the sections 11 and 12 constitute transverse supporting platforms for the tube when the filler element is formed by folding the component parts of the lateral body portion 3.

Wing portions 18 and 19 are a continuation of transverse portions 11 and 12 respectively, said wing portions having laterally extending side portions 20 and 21 respectively, of sufficient length to define the desired width of the filler member 3.

To provide additional side walls for end closures (hereinafter described) of the filler member, the transverse platforms 11 and 12 have extending wing portions 22, 23, and 24, 25, respectively, which are adapted to fold along suitable score lines. It will be noted that the portions 23 and 25 are cut out, preferably with round corners, from the main body portion 2 and are of less width than the wing extensions 22 and 24.

Referring particularly to Fig. 2, it will be seen that the several wing portions just described are

foldable along the edges of the transverse platforms 11 and 12 so as to constitute side walls of end closures 27 and 28 which are completed by folding upwardly the transverse platforms 11 and 12 along their score lines 26, and when thus folded, the outer edges of the wing members forming said closures abut against each other, thus completing the filler construction (see Fig. 3). It is obvious that the wing portions 23 and 25 function primarily as reinforcing means and also facilitate the folding of the wrapper element about the filler element as will be apparent hereinafter.

The first operation in packaging the tube is to fold the various wing sections comprising the end closures 27 and 28, and as a part of this operation the tip 15 of the tube is inserted in the aperture 13 and the prongs 17 extend through the aperture 14, thus securely suspending the tube between the transverse platforms 11 and 12 and completely enclosing it within the filler element. The wrapper is then folded around the filler by sequentially bending the successive side walls 5 to 9 along the score lines 4 which define side walls of a width to form an outer container which fits snugly against the filler element.

It will be observed that the width of the side walls 5 to 9 is slightly in excess of the width of the filler element so as to permit the folding of these walls about the filler element but in snug contact therewith so that there is no space between the wrapper and the filler and by this construction the two major portions 2 and 3 reinforce each other when the carton is assembled. It will also be noted that the depth or location of the transverse supporting platform sections 11 and 12 is sufficient to protect the tip 15 and the prongs 17 of the tube from end-wise exposure.

This step just described in the packaging of the tube may be regarded in the nature of a rolling operation and when the side walls 5 to 9 have been thus wrapped about the filler element they may be locked in place by any suitable fastening means. In the present instance, I have provided a suitable slot 30 located preferably along one of the longitudinal edges of the side wall 6. A locking tab 31 is provided on the outer edge of the side wall 9 and the tab 31, although appreciably greater in width than the length of the slot 30 is adapted to be inserted therein with slight manipulation on the part of the operative.

By virtue of the locking means provided for the filler element and the outer wrapper, no stitching or gluing is necessary to hold the carton in an assembled position. Through the elimination of any stitching or gluing operations in pre-fabrication or during the assembly of my carton, a saving in time is effected with a consequent saving in cost. It is also apparent that by the simplicity of the construction of my carton, tedious packing operations are eliminated, as is the case wherever an inner filler is provided that must be folded separately and inserted within some form of an outer container. That is to say, by reducing the number of parts constituting the carton the packaging of the tube is greatly facilitated. By avoiding the duplication of side walls which is more or less inherent in a carton composed of several separate parts, a substantial saving of stock material is thus effected.

When the tab 31 has been inserted within the slot 30, it functions as a detent, and the slot 30 serves as a keeper therefor. By the simple expedient of making the tab 31 wider than the

length of the slot 30, when the wrapper is locked about the filler member, the tube cannot be removed from the carton without evidence of mutilation of the outer wrapper. This arrangement provides a safety feature or means of indicating to the wary purchaser whether there has been any tampering or substitution of the tube for the one originally packaged.

Modifications in the construction of my carton will suggest themselves to those skilled in the art, but it is my intention to cover all such modifications as come within the scope of the appending claims.

What is claimed is:

1. A carton for radio tubes and the like formed from a one piece blank consisting of a major longitudinal wrapper portion and a major filler portion, the wrapper portion being provided with transverse score lines dividing it into a series of sections adapted to constitute side walls when folded along the score lines, one of the end side walls forming an outer side wall of the filler portion and having laterally extending therefrom contiguous wing sections, each of the wing sections being adapted to form transverse end platforms having die-cut apertures in axial alignment and adapted to accommodate the tip and prongs respectively of the tube, said platforms being reinforced by foldable side and end sections contiguous with the platforms and designed to enclose the tube suspended between the apertures of the platforms, the opposite end side wall of the wrapper portion having a tab adapted to engage a slot provided along one of the longitudinal edges of the side wall adjacent to the filler portion, whereby when the filler element is folded to suspend the tube between the transverse end platforms the wrapper portion may be rolled about the loaded filler and held locked by engagement of the tab with the slot.

2. A carton for radio tubes and the like formed from a one piece blank of paperboard consisting of a major longitudinal wrapper portion and a major filler portion, the wrapper portion being foldable about the filler member and provided with transverse score lines dividing it into a series of sections adapted to constitute side walls when folded along the score lines, one of the end side walls forming an outer side wall of the filler portion and having laterally extended therefrom contiguous wing sections, each of said sections being adapted to form transverse end platforms having die-cut apertures in axial alignment and adapted to accommodate the tip and prongs respectively of the tube, said platforms being reinforced by foldable side and end sections contiguous with the platform and designed to enclose the tube suspended between the apertures of the platforms, the side walls of the wrapper portion extending sufficiently beyond the transverse platform sections to protect the tip and prongs of the tube from endwise exposure, the opposite end side wall of the wrapper portion having a tab adapted to engage a slot provided along one of the longitudinal edges of the side wall adjacent to the filler portion, whereby when the filler element is folded to suspend the tube between the transverse end platforms the wrapper portion may be rolled about the loaded filler and held locked by engagement of the tab with the slot.
